A. L. LAMAR.

FUEL SUPPLY SYSTEM FOR INTERNAL COMBUSTION ENGINES.

APPLICATION FILED JUNE 21, 1917.

Patented Mar. 7, 1922.

1,408,749.

UNITED STATES PATENT OFFICE.

ALEXIS L. LAMAR, OF PITTSBURG, KANSAS.

FUEL-SUPPLY SYSTEM FOR INTERNAL-COMBUSTION ENGINES.

1,408,749.

Specification of Letters Patent.

Patented Mar. 7, 1922.

Application filed June 21, 1917. Serial No. 176,098.

To all whom it may concern:

Be it known that I, ALEXIS L. LAMAR, a citizen of the United States, residing at 114 West Monroe St., Pittsburg, in the county of Crawford and State of Kansas, have invented certain new and useful Improvements in Fuel-Supply Systems for Internal-Combustion Engines; and I do hereby declare the following to be a full, clear, and 10 exact description of the invention, such as will enable others skilled in the art to which it appertains to make and use the same.

This invention relates to a fuel supply system for internal combustion engines and 15 has for its principal object to provide a system of this character wherein gasoline may be used to initially start the engine after which kerosene may be used as a motor fuel. Another object of the invention is to provide 20 a kerosene supply tank and a gasoline supply tank which are connected to the carbureter of the engine, suitable means being provided for selectively controlling the admission of the kerosene or gasoline to the 25 carbureter.

A still further object of the invention is to provide a double acting dash pump which is connected to the drain cock of the carbureter and to the kerosene supply pipe where- 30 by upon opening of the drain cock of the carbureter and the actuation of the pump, the kerosene or heavier hydrocarbon may be pumped from the carbureter back into the kerosene supply tank, so as to permit of an 35 initial starting charge of gasoline to be deposited within the carbureter to facilitate easy and ready starting of the engine.

With these and other objects in view as will appear as the description proceeds, the 40 invention comprises the various novel features of construction, combination and arrangement of parts as will be more fully described hereinafter and set forth with particularity in the appended claims. Refer- 45 ring to the drawings.

Figure 1 is a side elevation of my improved fuel supply system, showing the various parts of it diagrammatically arranged.

Figure 2 is a horizontal sectional view 50 taken on the line 2--2 of Figure 1, and

Figure 3 is a vertical sectional view 55 through the lower end portion of the dash pump.

Similar characters of reference are used 60 to denote corresponding parts throughout

the accompanying drawings and the following description.

It is of course to be understood that my improved construction of fuel supply system may be used in connection with internal 60 combustion engines having an intake manifold and a carbureter of any well known or standard construction, however, in this instance, I have shown my fuel supply system arranged in connection with an internal 65 combustion engine having a kerosene vaporizing intake manifold, such as is shown and described in my application Serial No. 109,437 filed July 15, 1916.

Referring more particularly to the drawings the reference numeral 1 indicates the intake manifold which is connected to the engine 2 and is provided with a lateral extension 3 to which is connected the lateral extension 4 of the carbureter 5. 75

A three-way valve 6 is tapped through the vertical wall of the carbureter and consists of a casing 7 having oppositely disposed arms 8 and 9 and an externally threaded nipple 10 which is threaded through the 80 vertical wall of the carbureter. Rotatably mounted within the casing 7 is a valve 11 having a three-way passage 12 extending through it in a horizontal plane and adapted to selectively register with the extensions 85 8, 9 and 10 of the casing for a purpose which will presently appear.

One end of the gasoline supply pipe 13 is connected to the extension arm 9 by a union nut 14 while the other end of the supply pipe is connected to a gasoline reserve 90 or supply tank 15.

The extension arm 8 has one end of the kerosene supply pipe 16 connected to it through the medium of a union nut 17 while the opposite end of the kerosene supply pipe is connected to a main supply tank 18. 95

The upper end of the valve 11 is provided with a valve stem 19 which carries a head 20 provided with a pair of diametrical openings through which projects the forked end 21 of an operating rod 22 that extends upwardly through the dash 23 of the motor vehicle and is provided with an operating handle 24 by which the valve 11 may be rotated to selectively establish communication between either the kerosene or gasoline supply tanks and the carbureter. 100

The fuel supply system also includes a dash pump 25 which embodies a cylindrical 110

casing 26, the lower end of which is provided with a pair of diverging legs 27 and 28 in which are arranged check valves 29 and 30 respectively. The leg 27 of the pump has 5 one end of a conveyor pipe 31 connected to it by a union nut 32 while the other end is connected to the kerosene supply pipe 16 by a T-coupling 33.

The other leg 28 of the pump has one end 10 of a conveyor pipe 34 connected to it by a union nut 35 while the other end of the conveyor pipe is connected to the drain cock 36 of the carbureter, this drain cock being common to all carbureters.

15 A piston 37 is arranged within the pump casing 26 and is provided with an operating handle 38.

In the operation of the device when it is desired to initially start the engine, the valve 20 11 is rotated so as to close communication between the supply pipes 13 and 16 and the carbureter, or if desired the valve may be rotated so as to close communication between the supply pipe 16 and the carbureter and establish 25 communication between the supply pipe 13 and the carbureter. When the valve has been so turned and set, the pump 25 may be actuated so as to draw all of the kerosene or heavier hydrocarbon from the carbureter and subsequently pump it back into 30 the kerosene supply tank, the vacuum in the carbureter created by this action will draw in an initial charge of gasoline through the supply pipe 13 and fill the carbureter for an 35 initial starting of the engine.

It is of course to be understood that in order to effectively pump the kerosene from the carbureter back into the kerosene supply tank 18 that the check valve 30 must necessarily open inwardly while the check valve 29 opens outwardly under the action of the piston 37.

After the motor has been started and becomes sufficiently heated, the operating 45 handle 24 is turned so as to rotate the valve 11 to shut off communication between the gaso-

lene supply pipe 13 and the carbureter and establish communication between the kerosene supply pipe 16 and the carbureter, so that kerosene may be used as a fuel for consumption by the engine under ordinary running conditions.

From the foregoing description taken in connection with the accompanying drawings, the advantages of construction and the method of operation will be readily apparent to those skilled in the art to which this invention relates, and while I have described the principle of operation of the invention, I desire to have it understood that such changes in construction and arrangement of parts may be made when desired as are within the scope of the appended claims.

What I claim is:

1. The combination with a carbureter provided with a feed reservoir, connections therefor to a gasoline source of supply and to a kerosene source of supply, inter-dependent valve mechanism for controlling said connections, whereby either fuel supply may be connected to said reservoir and the other thereby cut off, a pump, and connections for said pump to said feed reservoir and kerosene supply, whereby the fuel may be withdrawn from said feed reservoir by said pump 75 and returned to said kerosene supply.

2. The combination of a carbureter, provided with a feed reservoir, separate pipes therefrom to a gasoline source of supply and to a kerosene source of supply, valve mechanism for controlling said pipes whereby either fuel supply may be connected to said feed reservoir and the other cut off, a pump, and connections for said pump to said feed reservoir and to the kerosene supply pipe 85 whereby the fuel may be withdrawn from said feed reservoir by said pump and returned to said kerosene supply through said kerosene supply pipe.

In testimony whereof I have signed my 90 name to this specification.

ALEXIS L. LAMAR.
